UNITED STATES PATENT OFFICE.

THOMAS BOOTH, OF BOISE, IDAHO.

FIRE-ESCAPE.

1,123,229.

Specification of Letters Patent.

Patented Jan. 5, 1915.

Application filed October 6, 1913. Serial No. 793,624.

To all whom it may concern:

Be it known that I, THOMAS BOOTH, a citizen of the United States, residing at Boise city, in the county of Ada and State 5 of Idaho, have invented certain new and useful Improvements in Fire-Escapes, of which the following is a specification.

This invention relates to an improvement in fire escapes.

10 The primary object of the invention is to improve the construction shown in my patent granted the 9th day of September, 1913. The structure illustrated in said patent consists of a casing rectangular in cross section and formed with an opening and a cable on which the casing is slidably mounted, the casing supporting a plurality of brakes or clutches for engaging the cable to retard the progress of the casing on the 15 cable. In this construction the body support is connected to one of the clutch members, and the present invention is designed particularly to improve the construction and arrangement of the body support as well as the 20 means for clutching the cable to retard the progress of the casing.

25 A further object of the invention is to provide means whereby the casing is fed at a moderate rate of speed along the cable, said means acting independently of the clutch mechanism.

30 In the drawings: Figure 1 is a side elevation. Fig. 2 a vertical section. Fig. 3 a section on the line 3—3 of Fig. 2. Fig. 4 a 35 front elevation.

Corresponding and like parts are referred to in the following description and indicated in all the views of the accompanying drawings by the same reference characters.

40 In the drawings, 10 designates the casing which is substantially rectangular in cross section, the casing including side walls 11 and 12 and end walls 13 and 14. The side wall 12 terminates short of the end wall 13, 45 thereby providing an opening through which the cable is passed in positioning the same within the casing. The end wall 13 is more extensive than the end wall 14, projecting beyond the side wall 12 and forming 50 a stop for a latch member. This latch member consists of a plate 15 pivotally connected to the wall 12 of the casing adjacent its lower end. This plate extends the entire length of the casing and is formed with 55 the offset portion 16, which extends beyond the casing. The plate, as will be noted from

Fig. 1, extends across the slot between the edge of the wall 12 and the wall 13, thus preventing displacement of the cable.

The wall 13, adjacent its upper end, is 60 formed with an opening 17, the plate 15 being provided with an extension 18 which projects through said opening when the plate is in closed position. The plate is held in closed position by a latch 19 which 65 consists of a strip of resilient material secured to one edge of the plate and formed with a stud, which extends within an opening formed in the wall 12 of the casing. It will be noted by this construction that the 70 cable, after being positioned within the casing, is effectually held against displacement.

The body support consists of a yoke 20 which is pivotally mounted between the side walls of the casing, being supported on the 75 shaft 20' arranged at the base of the casing. Attention is called to the fact that the weight of the body is on the casing and not on the rope clutch as in my former patent. It will also be seen that any form of belt or 80 support may be attached to the yoke and conveniently removed when not in use. A plate 21 is secured to the wall 11 of the casing, said plate extending beyond the upper end of the casing and forming a support 85 for a shaft 21' on which a roller 22 is mounted, there being a plate or disk 22' arranged on the end of the shaft remote from the plate. The roller extends transversely of the casing, whereby the cable 23 may be 90 looped over the same. It will be noted that with the cable looped over the roller 22, the weight of the body exerted on the casing will draw the roller in binding contact with the cable to retard the progress of the casing, allowing for gradual descent. The 95 rope clutch consists of a block 24 pivotally mounted within the casing, the face 25 of said block being adapted to bear on the cable to stop the casing or to retard its progress. A lever 26 is mounted on the lower end of the block, said lever extending through a slot 27 arranged in the wall 14 of the casing.

When the device is in use and the cable 105 positioned within the casing, the clutch block 24 is held in contact with the cable until the occupant has been seated in the sling or basket attached to the yoke 20. The clutch is then released to an extent, 110 whereby the casing will slide gradually over the cable, its progress being retarded by the

roller 22 as well as the clutch 24. It will be noted by this construction that the speed at which the casing travels over the cable may be conveniently regulated by the occupant and that the weight of the body supported by the yoke 20 will cause a gradual descent of the casing whenever the clutch is brought out of contact with the cable. It will be noted, however, that the clutch member may be brought in contact with the cable to stop the casing at any point along the cable, thereby allowing the occupant to descend from one floor of the building to another. It will be noted that when the plate 15 is closed, its extension 16 is disposed to close the opening between the upper end of the casing 10 and the adjacent edge of the disk 22', thus forming a guard to prevent the cable when slackened, from uncoiling from around the roller 22 and becoming displaced therefrom by slipping over the free extremity of the shaft supporting said roller. Thus, when the plate 15 is brought into locked position, it not only prevents the cable from being removed from the casing but also forms a continuation of the side wall of the casing, whereby the cable is maintained on the roller as effectually as if the roller were disposed between and secured to the end walls of the casing. Attention is also called to the fact that the structure is such that it may be easily and economically manufactured and that the various parts may be readily assembled. It will be obvious that when not in use, the device may be readily removed from the cable, the roller being so supported that the cable may be removed from the same without disconnecting the cable from the building. Thus, the device may be quickly attached to the cable and brought into use by merely looping the cable over the roller, passing the same through the slot formed

in the casing and locking the plate 15 to the casing. It will be noted that any suitable form of sling or basket may be attached to the supporting yoke and that the operation of the device does not depend on the construction of the body supporting means.

It will be noted that the offset portion 16 of the plate 15 extends beyond the upper end of the casing 10 and terminates at its free extremity adjacent the edge of the plate 22', forming a closure for the opening between said plate and the casing and providing a cable retaining guard for the roller 22 preventing displacement over the free extremity of the standard supporting the roller of the portion of the cable coiled around the roller, which might otherwise occur when the device was not in use and the cable became slackened.

Having thus described my invention, what I claim as new is:

A device of the character described including a casing having a slot formed therein, a roller supported upon the casing and spaced from one end thereof, one extremity of said roller being free, a plate carried at the free extremity of the roller, a cable insertible in the casing through said slot and between the plate carried at the free extremity of the roller and the adjacent end of the casing, said cable engaging the roller, means carried by the casing to frictionally engage the cable, a body support mounted upon the casing, and a closure plate shiftably mounted upon the casing, the free extremity of said plate forming a cable retaining guard for the roller.

In testimony whereof I affix my signature in presence of two witnesses.

THOMAS BOOTH. [L.S.]
